UNITED STATES PATENT OFFICE.

THOMAS J. McCARTHY, OF NEW YORK, N. Y., ASSIGNOR TO AUTO-MARINE EQUIPMENT CO., OF NEW YORK, N. Y., A CORPORATION OF ARIZONA.

STARTING DEVICE FOR INTERNAL-COMBUSTION ENGINES.

1,149,661.

Specification of Letters Patent. Patented Aug. 10, 1915.

Application filed May 14, 1914. Serial No. 838,507.

To all whom it may concern:

Be it known that I, THOMAS J. McCARTHY, a citizen of the United States, residing at New York city, in the county of New York and State of New York, have invented certain new and useful Improvements in Starting Devices for Internal-Combustion Engines, of which the following is a specification.

10 My invention relates to starting devices for internal combustion engines and is especially adapted for the engines of automobiles, the present invention being an improvement upon my former Patent No. 15 1,046,825.

One of the objects of my invention is to provide a means for readily supplying the cylinders of an engine with an initial proper gaseous mixture while the engine is at rest, 20 so that it will instantly start into operation upon the application of the ignition spark, in contradistinction to the usual priming devices which merely introduce a gasolene spray.

25 One of the purposes of my invention is to provide an apparatus which may be applied to existing engines and to arrange the controlling parts, that they may be operated by the driver while in position at the 30 steering wheel.

In the accompanying drawings, Figure 1, is a side elevation of an apparatus embodying my invention, showing the manner of attaching it to the engine; Fig. 2, is a vertical section of the apparatus on line 2—2 of Fig. 3; Fig. 3, is a cross-section on the line 3—3 of Fig. 2; Fig. 4, is a cross-section on the line 4—4 of Fig. 2; Fig. 5, is a vertical section of the apparatus on the line 40 5—5 of Fig. 4; Fig. 6, is an enlarged detail in section of the pump air inlet valve; Fig. 7, is a vertical section of the priming cup and attached parts; Fig. 8, is a side elevation of another form of the priming 45 cup; Fig. 9, is a top plan view of the priming cup; Fig. 10, is a side elevation of a modified arrangement of my starting device showing the manner of attachment to the dash-board of an automobile; Fig. 11, is a 50 front elevation of the same; and Fig. 12, is an enlarged sectional view on the line 12—12 of Fig. 11.

For purposes of illustration I have shown my starter connected to a four cylinder internal combustion engine 2, having a carbureter 4, connected to the manifold 6, leading to the respective cylinders of the engine, and the usual water circulating pipes 8, leading to the radiator 10. 55

My starting device is entirely independent of the carbureter and is connected by separate pipes 12, directly with the several engine cylinders and not by way of the manifold, which insures position and certain action in the cylinders upon the pistons. The main tank 14 of the starter is preferably bolted at 15, 15' to the dash board 17. 60

The tank cover 18 is provided with a depending annular rim which is threaded upon 70 the tank and is made air tight by a gasket 19, preferably fitting in an annular recess.

A filling aperture is closed by the screw plug 20, and a pressure gage 22, is threaded into an apertured boss 23. 75

A squared or hexagonal boss 24 is adapted to receive a wrench to tighten or remove the cover.

The tank 14 is provided with internal air ducts, terminating just below the top and 80 which are preferably formed by tubular ribs 26, 27 cast integral with the walls of the tank and which, in effect, form air ducts within the walls. The duct through stem 26, connects at its lower end with a cross-duct 29, having a port 30, leading into the pump barrel 32, and controlled by a valve 34. This valve is provided with a guiding stem which extends into a recess in the plug 36, and is normally spring-pressed upwardly 85 against its seat as shown in Fig. 5. Access to the channel 29, may be had by removing the plug 38. When the pump piston 40 is drawn upwardly by the handle 42, air is drawn into the pump barrel through the 90 valve 43, the ball check 45 being lifted and which may be screwed into the bottom of the pump cylinder. Upon the return stroke the ball closes the check valve 43 and the valve 34 is forced downwardly in opposition to its 95 spring permitting the air to pass through the duct 26 into the tank 14. The pump cylinder is shown as screwed into a socket 44, forming the bottom of the pump barrel, 100

2
and cast integral with the tank, but it is evident that the pump may be cast to the tank or otherwise secured thereto.

Cast integral with the bottom of the tank 5 are ribs 47, 48 and 49 which converge and unite in a central boss 50 and these ribs contain ducts which intersect in the central boss. The duct 52 in the rib 47, extends from the lower end of the air-duct 27, but is 10 closed at the outer end. The duct 53 in the rib 48, is open at the outer end and receives an aperture threaded nut 54, through which extends the threaded stem of a needle valve 56, which is operated by a thumb-piece 57. 15 The duct 53 is interiorly shouldered to receive a washer 58, a packing 59 being held between the washer and the nut 54. The duct 53 connects with the outlet opening 60, in the bottom wall of the fuel supply 20 tank 14, as shown in Fig. 2. The inner end of both ducts 52 and 53 are reduced in diameter to small passages or channels.

The rib 49 contains a large duct 65, which constitutes a mixing or gasifying chamber, 25 and from which lead the several ducts passing into the nipples 67, which connect with the several distributing tubes 12, leading to the engine cylinders.

The outer end of the duct 65 is shouldered 30 to receive the washer 68, against which the packing 70 is held by the nut 72, the latter having a threaded aperture to receive the stem of the main air and fuel controlling 35 valve 75, having an operating handle 76, secured to the outer end of the stem 77.

By referring to Fig. 2, it will be observed that the inner reduced ends of the air and fuel ducts 52 and 53 intersect below the central axis of the valve 75, so that as the 40 valve 75 is withdrawn, the stream of gasoline or other fuel issuing from the duct 53 impinges directly upon the blast of air issuing under great pressure from the duct 52 underneath the valve 75. If these ducts were not eccentric but were in line with the axis of the valve 75, the stream of air and the jet of gasoline would not meet unless the valve 45 were completely withdrawn into the chamber 65, but would strike opposite sides of the valve. The result would be a mixture of air and more or less finely divided particles of gasoline but not in any sense a gaseous mixture. I have discovered that an instantaneous explosive gaseous mixture is obtained only if the jet of gasoline issuing 50 from the duct 53 receives the direct impact of the stream of air as it issues under high pressure from the duct 52. A jet of gasoline which is merely forced into the engine cylinders in the form of a spray even 55 under pressure from an atomizer will not form an explosive mixture and I wish herein to point out the radical difference between a mere priming mixture of atomized

gasoline and a vaporized gaseous explosive 65 mixture. The latter will explode in the normal manner under the action of an electric or other spark while the engine is still and cold but the former will not.

The explosive gaseous mixture fills the 70 mixing and distributing chamber 65 and from thence passes through the separate pipes 12 to the several combined gas inlet and priming valves 80, connected to the respective engine cylinders, as shown in Fig. 75 1. The spark plugs are indicated at 82.

The construction of my combined gas inlet and priming cock is shown in Figs. 7, 8 and 9. The threaded end of the stem or standard 83, screws into the end of the engine cylinder and is secured by a lock-nut 84. The upper end of the stem carries a bowl 86, which may be used as a priming cup when a priming or cleansing liquid is to be introduced into the cylinder. A 85 branch stem 83^a carries a casing head 87, having a ball check 88, operating in a cavity 89 closed by a screw 90. The lower end of the casing 87 is provided with a threaded recess to receive an apertured clamping nut 90 91, and has a tapering inner end to receive a wedge-shaped bushing 92. The end of the gaseous fuel pipe 12 passes through the aperture in the nut 91 and through the bushing which is wedged tightly around the 95 pipe by means of the nut.

At the intersection of the ducts passing through the main and branch stems, I provide an enlarged transverse aperture which is tapered to receive a tapered valve stem 100 95, held in position by a spring 96, bearing against a boss on the stem and a washer 97 held by a pin 98 in the small end of the valve stem. The opposite end of the valve 105 stem is provided with a wing 99 by which it may be turned through 90°, between the stops 101 and 102 projecting from the main stem 83. The valve stem 95 is provided with a duct extending transversely therethrough and a branch duct leading at right 110 angles thereto upon one side only, as shown in Fig. 7. It is evident, therefore, that when the valve is in the position indicated in Fig. 7, a passage extends therethrough connecting the ducts in the main and branch stems so 115 that fluid pressure in the pipe 12 may lift the ball check 88 and pass through the branch and main stems into the engine cylinder. If the valve stem 95 is turned through 90° into its other position, the 120 branch port will extend to the left, and the through port will connect the priming cup 86 with the duct through the main stem 83, while the solid sector of the valve stem 95 125 will close off the duct in the branch stem 83^a. The advantages of this compact valve construction will be apparent to engineers.

The operation of my invention will be

apparent from the foregoing description of the separate parts of the apparatus. The tank 14 having been filled, the hand pump 42 is given a few strokes until the gage 22 5 indicates the desired pressure, say from 125 to 150 pounds, thereby subjecting the gasoline in the tank and the air in the duct 27 to this pressure. The needle valve 56 is opened the desired amount and finally the 10 main controlling valve 75 is opened. The jet of gasoline passing through the opening 60 and issuing through the duct 53 is struck by the air-blast issuing from the duct 52 which instantly vaporizes the liquid and the 15 resulting explosive gaseous mixture is forced into the engine cylinders, it being understood that the valves 95 are in the position shown in Fig. 7. The instant the sparking apparatus is set in operation, the explosive 20 mixture will be exploded in the cylinders and the engine will start.

In Fig. 1, I have shown the tank and pump attached to the inside of the dash board but it is sometimes desirable to mount 25 the fuel tank upon the outside of the dash board and in that case, I prefer to connect the pump in a diagonal manner and preferably supporting the upper end in a plate 33, secured to the dash board as indicated 30 in Figs. 10 and 11. The gage 22, is screwed into a nipple 23^a, exteriorly threaded to receive a flanged nut 16, the nipple thereby serving also as a support for the tank. This arrangement requires less room on the 35 dash board and is less conspicuous. In either arrangement the operating parts of my vapor starter are within easy access of the operator while in position at the steering wheel.

40 I have now described in detail the construction illustrated in the accompanying drawings for the purpose of disclosing an embodiment of my invention, but I am aware that various changes may be made 45 therein within the scope of my claims and without departing from the spirit of my invention. I have pointed out wherein my invention differs from merely atomizing or spraying the gasoline or liquid fuel into 50 the engine. As distinguished from such prior devices my invention consists in instantaneously vaporizing liquid fuel to form an explosive gaseous mixture, simultaneously forcing said explosive gaseous mixture 55 directly into the engine cylinders and igniting the mixture to start the engine.

I claim:—

1. A vapor starting apparatus for internal combustion engines, comprising a liquid fuel 60 tank, means for placing a body of liquid fuel and a body of air within said tank under pressure, a mixing chamber connected by separate channels with said air and said liquid in the tank, controlling means for

causing a jet of air and a jet of liquid flowing through said channels to impact with each other in said chamber, and means for delivering the resulting explosive gaseous mixture directly into the engine cylinders. 65

2. A vapor starting apparatus for internal combustion engines, comprising a liquid fuel tank, tubes connected with the upper part of said tank and forming inlet and outlet air ducts, a pump connected to one end of said inlet duct, a tubular member 75 secured to the bottom of said tank forming a mixing chamber and having branch members provided with passages connected respectively to said outlet duct and to the lower part of said tank, a manually operated valve controlling the communication between said passages and said mixing chamber, and separate means connecting said chamber with the respective engine cylinders. 80

3. A vapor starting apparatus for internal combustion engines, comprising a liquid fuel tank, tubes connected with the upper part of said tank, and forming inlet and outlet air ducts, a pump connected to one end of 90 said inlet duct, a tubular member secured to the bottom of said tank forming a mixing chamber and having branch members provided with passages connected respectively to said outlet duct and to the lower 95 part of said tank, a valve controlling said passage into the tank, a manually operated valve controlling the communication between said passages and said mixing chamber, and separate means connecting said 100 chamber with the respective engine cylinders.

4. A vapor starting apparatus for internal combustion engines, comprising a liquid fuel tank, tubes connected with the upper part 105 of said tank and forming inlet and outlet air ducts, a pump connected, to one end of said inlet duct, a tubular member secured to the bottom of said tank forming a mixing chamber and having branch members provided with passages connected respectively 110 to said outlet duct and to the lower part of said tank, a manually operated valve controlling the communication between said passage and said mixing chamber, separate 115 means connecting said chamber with the respective engine cylinders, and means for separately controlling said connections with the cylinders.

5. In a starting apparatus for internal 120 combustion engines, a combined vapor inlet and priming cock for the engine cylinders, comprising a main stem or standard adapted to be threaded into the end of the cylinder and having a channel extending therethrough, a priming cup carried thereby and connecting with said channel, a branch stem having a channel intersecting the channel 125

4. in the main stem, a check valve in said branch channel, and a manually actuated valve at the intersection of said main and branch channels having main and branch 5 passages which may be turned to connect said passages and simultaneously close communication with said priming cup, or to connect said cup and main passage and

simultaneously close the passage through the branch channel.

In testimony whereof I affix my signature in presence of two witnesses.

THOMAS J. McCARTHY.
